(57) **CLAIM**

The ornamental design for a modular timer and cover, as shown and described.

DESCRIPTION

FIG. 1 is a perspective view of the timer cover illustrating our design, the modular timer being indicated by broken lines;

FIG. 2 is a rear perspective view thereof;

FIG. 3 is a front view thereof;

FIG. 4 is a right side view thereof, the left side being a mirror image thereof;

FIG. 5 is a rear view thereof;

FIG. 6 is a top view thereof;

FIG. 7 is a bottom view thereof;

FIG. 8 is a perspective view of the timer cover illustrating our design, the modular timer being indicated by broken lines;

FIG. 9 is a rear perspective view thereof;

FIG. 10 is a front view thereof;

FIG. 11 is a right side view thereof, the left side being a mirror image thereof;

FIG. 12 is a rear view thereof;

FIG. 13 is a top view thereof; and,

FIG. 14 is a bottom view thereof.

Any elements shown in broken lines form no part of the claimed invention, and are instead included to show environmental aspects of the claimed invention.
